UNITED STATES PATENT OFFICE.

HENRY J. EDLUND, OF BURLINGTON, VERMONT.

CAN OPENER.

Application filed May 24, 1924. Serial No. 715,631.

To all whom it may concern:

Be it known that I, HENRY J. EDLUND, a citizen of the United States, and a resident of Burlington, in the county of Chittenden and State of Vermont, have invented certain new and useful Improvements in Can Openers, of which the following is a specification.

My invention is an improvement in can openers of that type which affords facilities for rotating a can in contact with a cutting blade to effect cutting of the can top, and it consists in the combinations, constructions and arrangements herein described and claimed.

15 The present invention may be described as a branch or species of the broad invention disclosed in my prior application for Letters Patent of the United States, for improvements in can opening devices, Serial 20 #607,849, filed December 19, 1922.

In my aforesaid prior application I disclosed a novel can opening device having means for engaging with the peripheral wall of a can of any one of a considerable 25 range of sizes, to cause rotation of the can in engagement with a cutting blade together with an improved cutting blade adapted, on rotation of the can in engagement therewith, to roll the edge provided 30 by the cutting of the blade in the can so that the edge of the opening defined by the cut will be continuously smooth. Means also is provided in a device embodying the invention as disclosed in my aforesaid prior 35 application for adjusting the position of the cutting blade in respect to the marginal edge of the can which is to be opened through the use of the device so that the cutting blade will pierce the can top at a 40 point somewhat removed from the marginal edge of the can top and then will be moved in cutting engagement with the can top nearly to the marginal edge of the can top and practically the entire top will be severed 45 from the can when the latter has been completely rotated in engagement with the cutting blade.

An object of the present invention is to simplify the construction of a can opener 50 which will afford facilities for accomplish-

ing the results set out in the foregoing so as to provide a strong, durable, reliable and conveniently operable can opener which comprises but relatively few parts and which will be thoroughly practical commercially.

Other objects and advantages will be apparent from the following description, considered in conjunction with the accompanying drawings, in which:

Figure 1 is a view partly in side elevation and partly in vertical section, showing a can opener embodying the present invention in position for use.

Figure 2 is a section along the line 2—2 of 65 Figure 1,

Figure 3 is a section along the line 3—3 of Figure 1,

Figure 4 is a relatively enlarged fragmentary vertical sectional view, showing the 70 blade of the device in piercing relation to a can top close to the marginal edge of the latter and showing the means for controlling the movement of the blade in respect to the can and the means for rotating the can in 75 engagement with the cutting blade, and

Figure 5 is a fragmentary perspective group view, showing the major elements of the opener in drawn-apart detached position.

In carrying out my invention, I provide a post 1 which preferably is non-circular in cross sectional contour and is slidable in a vertical sleeve 2. The latter is attached to a table top 3 or like support by means of a clamp-screw 4 carried by a lug 5 extending laterally from the sleeve underneath the top 3 in conjunction with a horizontal plate 6 which is integral with and extends laterally from the sleeve 2 in overlying relation to the table top, the plate 6 being provided at its marginal edge with a depending flange 7 resting upon the table top and spacing the plate 6 from the table top. The plate 6 preferably is formed with openings receiving screws 8 which enter the table top and thus aid in securing the sleeve 2 to the table top 3 and in addition hold the plate 6 rigidly to the table top. The post 1 is slidable vertically in the sleeve 2 but is held against

rotation about the axis of the latter by reason of the engagement of the walls of the post with the inner wall of the sleeve.

- The post 1 is merged at its upper end into 5 the walls of a tubular housing 9 and the latter is fashioned to provide in its lower past a substantially cylindrical chamber 10 for the reception of a rotor 11. The rotor 11 is in the form of a disk having a threaded 10 central opening screwed on a reduced threaded portion 12 of a shaft 13 against a shoulder 14 on the latter. The shaft is disposed vertically in the tubular housing 9 and has the lower end portion 15 thereof 15 formed to have a diameter less than that of the threaded portion 12, said reduced lower end portion being journaled in a vertical socket 16 in the bottom wall of the chamber 10.
- 20 The housing 9 is provided with a lateral opening 17 opening from the outer wall thereof into the chamber 10 and located at the same side of the post 1 as the plate 6. The rotor 11 protrudes through the opening 25 17 from the chamber 10. The rotor 11 has a circumferentially extending series of teeth 18 on its periphery, the respective teeth being inclined in respect to the perpendicular.
- 30 The tubular housing 9 is provided at its upper end and at an appreciable distance above the chamber 10 with a lateral extension which extends laterally of the same side of the post 1 as the plate 6 and is formed to provide a pair of spaced ears 19 35 connected at their upper edges and merged into the walls of the housing 9 by a substantially horizontal web portion 20. The tubular housing 9 is in open communication with the space between the ears 19 and 40 an arm 21 of a bell crank lever 22 which is fulcrumed on a horizontal pin that is secured at its ends in alined openings in the ears 19 extends into the tubular housing 9, and is provided at its inner end with forks 45 23 adapted to slidingly embrace the shaft 13 and to rest upon a washer 24 which slides on the shaft 13. The extremities of the forks 23 preferably are rounded, as shown.
- 50 The other arm of the bell crank lever 22 is indicated at 25 and depends from the extension 19—20—19 alongside of the tubular housing 9 nearly to the level of the rotor 11. The arm 25 carries the cutter blade 27 which is secured thereto by fastening devices, as at 28. A stop screw 29 threadedly 55 engages alined openings in the arm 25 and the shank of the cutter blade and is adapted to abut the wall of the tubular housing when the blade is in the position shown in Figs. 60 1 and 4. A lock or jam nut on the outer end portion of the stop screw engages with the arm 25 to hold the screw in adjusted position in respect to the arm 25 and cutter blade 27. The cutter blade depends below 65 the lower end of the arm 25 and below the

level of the rotor 11. The specific blade which I prefer to employ is described in my aforesaid prior application for patent, but it may be mentioned herein that the lower end portion of the blade is adapted to pierce 70 the top of a can 30 which may be positioned upon the plate 6, as shown best in Figure 1, at a slight distance from the marginal edge of the can top and on actuation of the bell crank lever in a manner to be presently described, to move radially outward in cutting engagement with the can top almost to marginal edge of the can top and then when the can is rotated to cut the can top along the marginal edge of the latter. 80

An expansion spring 31 encircles the shaft 13 between the washer 24 and an inwardly extending annular stop 32 which is formed on the inner wall of the housing 9 at the upper end of the chamber 10. The action 85 of the spring 31 tends to raise the washer 24 and the arm 21 of the bell crank lever and thus to swing the knife carrying arm 25 inward. A sleeve plunger 33 which has limited sliding movement on the upper end portion of the shaft 13 will be moved downward from the position shown in Figure 4 and by the full lines in Figure 1 to the position illustrated by the dotted lines in Figure 1, when a crank handle 34 having a pair 90 of spaced cam ears 35 straddling an upstanding lug 36 at the upper end of the shaft 13 and pivotally attached by a horizontal pin 37 to the latter has been swung from the position indicated by the dotted lines in Figure 1. This downward movement of the plunger will be caused by the contact of the cam ears 35 therewith and will be against the action of the spring 31. A flange 38 at the upper end of the plunger 95 serves to give the cam portion of the handle a relatively large bearing surface. When the handle 34 is in the position indicated by the dotted lines in Figure 1, the arm 21 will have been swung downward in the tubular housing from the position shown in Figure 4 and the arm 25 will have been swung outward from the position shown in full lines in Figures 1 and 4. As soon as the handle 34 has been swung to horizontal position, the sleeve plunger is moved upward in response to the actuation of the spring 31 to an extent sufficient to permit swinging movement of the arm 25 inward until the stop 29 abuts the tubular housing. 100

From the foregoing description of the various parts of the device, the operation thereof may be readily understood. Cans of various sizes, shapes and types of construction can be opened through the use of the device. A can of a given size and shape is placed upon the plate 6 which may be termed a table and the post 1 with the parts carried thereby, as hereinbefore described, is adjusted vertically in the sleeve 2 until 105 120 125 130

the cutter blade 27 rests upon the top of the can at a point somewhat removed from the marginal edge of the can, the handle 34 being in raised or upward swung position. It is to be understood that the can is disposed on the plate 6 so that the outer face of the body thereof will be in contact with the teeth on the periphery of the rotor 11. A slight blow or pressure on the top 10 of the handle will cause the cutter blade to penetrate the can top. The handle 34 now is swung to lowered position and the consequent movement of the bell crank lever will force the blade radially outward in 15 cutting engagement with the can top nearly to the marginal edge of the latter. The edge portion of the can top that will margin the opening which will be provided when the can has been completely rotated 20 in engagement with the cutter blade will be turned downward and will have a continuously smooth edge, thus obviating the cutting or tearing of the fingers of the operator and permitting the removal intact 25 of the contents of the can. The rotation of the can is caused by the engagement of the teeth of the rotor therewith when the latter is operated. The rotor is operated by turning the shaft 13 through the agency of 30 the handle 34. The engagement of the teeth with the body of the can at the upper end of the latter is at a point close to the point of cutting action of the blade 27 at any given time and the inclination of the 35 teeth 18 is such that the can will be fed or forced upward against the cutting edge of the blade 27 by the action of the teeth of the rotor on the can.

Obviously, the invention is susceptible of 40 embodiment in forms other than that which is illustrated in the accompanying drawings, and I therefore consider as my own all such modifications and adaptations thereof as fairly fall within the scope of the 45 appended claims.

I claim:-

1. In a can opening device, a vertically adjustable post, a horizontal support at one side of said post and adjacent thereto on 50 which a can may be disposed, a blade, means carried by said post for adjustably supporting said blade above said horizontal support and in position to penetrate the top of the can on said horizontal support, a 55 rotor supported on said post for engaging with said can to feed the latter to said blade, a sleeve movable on said post in engagement with said blade supporting means for actuating the latter to move the blade 60 radially of the can top, and a handle pivoted to the post for turning the latter and having a cam for actuating said sleeve.
2. In a can opening device, a table on 65 which a can may rest, a post at one edge of the table, a tubular housing at the upper
- end of the post having a pair of horizontally spaced ears extending above the table laterally of the housing from a lateral opening in the housing, a vertical shaft journaled in said housing, a rotor secured on said shaft 70 and protruding through a second and lower lateral opening in the housing and having teeth on the periphery thereof for engaging with the can on said table, a bell crank lever fulcrumed to swing about a horizontal axis 75 between said ears, said lever having an arm extending through said first named opening into said housing and having the second arm thereof depending alongside of the tubular housing, a blade carried by said depending 80 arm for cutting engagement with the top of the can on said table, spring means within said housing urging said first named lever arm upward to effect movement of the blade toward the marginal edge of the can top, 85 and means for rotating said shaft.
3. In a can opening device, a table on which a can may rest, a post at one edge of the table, a tubular housing at the upper end of the post having a pair of horizontally spaced ears extending above the table laterally of the housing from a lateral opening in the housing, a vertical shaft journaled in said housing, a rotor secured on said shaft and protruding through a second and lower lateral opening in the housing and having teeth on the periphery thereof for engaging with the can on said table, a bell crank lever fulcrumed to swing about a horizontal axis 90 between said ears, said lever having an arm extending through said first named opening into said housing and having the second arm thereof depending alongside of the tubular housing, a blade carried by said depending arm for cutting engagement with the top of the can on said table, spring means within said housing urging said first named lever arm upward to effect movement of the blade toward the marginal edge of the can top, 95 and means for rotating said shaft.
4. In a can opening device, a table on which a can may rest, a post at one edge of the table, a tubular housing at the upper end of the post having a pair of horizontally spaced ears extending above the table laterally of the housing from a lateral opening in the housing, a vertical shaft journaled in said housing, a rotor secured on said shaft and protruding through a second and lower lateral opening in the housing and having teeth on the periphery thereof for engaging with the can on said table, a bell crank lever fulcrumed to swing about a horizontal axis 100 between said ears, said lever having an arm extending through said first named opening into said housing and having the second arm thereof depending alongside of the tubular housing, a blade carried by said depending arm for cutting engagement with the top of the can on said table, spring means within said housing urging said first named lever arm upward to effect movement of the blade toward the marginal edge of the can top, 105 and means for rotating said shaft.
5. In a can opening device, a table on which a can may rest, a post at one edge of the table, a tubular housing at the upper end of the post having a pair of horizontally spaced ears extending above the table laterally of the housing from a lateral opening in the housing, a vertical shaft journaled in said housing, a rotor secured on said shaft and protruding through a second and lower lateral opening in the housing and having teeth on the periphery thereof for engaging with the can on said table, a bell crank lever fulcrumed to swing about a horizontal axis 110 between said ears, said lever having an arm extending through said first named opening into said housing and having the second arm thereof depending alongside of the tubular housing, a blade carried by said depending arm for cutting engagement with the top of the can on said table, spring means within said housing urging said first named lever arm upward to effect movement of the blade toward the marginal edge of the can top, 115 and means for rotating said shaft.
6. In a can opening device, a table on which a can may rest, a post at one edge of the table, a tubular housing at the upper end of the post having a pair of horizontally spaced ears extending above the table laterally of the housing from a lateral opening in the housing, a vertical shaft journaled in said housing, a rotor secured on said shaft and protruding through a second and lower lateral opening in the housing and having teeth on the periphery thereof for engaging with the can on said table, a bell crank lever fulcrumed to swing about a horizontal axis 120 between said ears, said lever having an arm extending through said first named opening into said housing and having the second arm thereof depending alongside of the tubular housing, a blade carried by said depending arm for cutting engagement with the top of the can on said table, spring means within said housing urging said first named lever arm upward to effect movement of the blade toward the marginal edge of the can top, 125 and means for rotating said shaft.
7. In a can opening device, a table on which a can may rest, a post at one edge of the table, a tubular housing at the upper end of the post having a pair of horizontally spaced ears extending above the table laterally of the housing from a lateral opening in the housing, a vertical shaft journaled in said housing, a rotor secured on said shaft and protruding through a second and lower lateral opening in the housing and having teeth on the periphery thereof for engaging with the can on said table, a bell crank lever fulcrumed to swing about a horizontal axis 130 between said ears, said lever having an arm extending through said first named opening into said housing and having the second arm thereof depending alongside of the tubular housing, a blade carried by said depending arm for cutting engagement with the top of the can on said table, spring means within said housing urging said first named lever arm upward to effect movement of the blade toward the marginal edge of the can top, and means for rotating said shaft.

having an arm extending through said first named opening into said housing and having the second arm thereof depending alongside of the tubular housing, a blade carried by said depending arm for cutting engagement with the top of the can on said table, spring means within said housing urging

said first named lever arm upward to effect movement of the blade toward the marginal edge of the can top, means for rotating 10 said shaft and a stop for limiting the swinging movement of said bell crank in response to the actuation of said spring.

HENRY J. EDLUND.
